KARL E. AHLBERG, OF CULVER CITY, CALIFORNIA

FLUID PUMP

Application filed March 22, 1929. Serial No. 349,220.

This invention relates to fluid pumps, and has for its object to provide a novel construction in pump mechanism including a stationary housing and an oscillatory impeller by means of which a flow of liquid to the pump chamber and the discharge of the same therefrom is effected when the impeller is rocked or oscillated in progressive fashion about a changing fulcrum substantially in accordance with the movement produced by rolling one cone over another.

Another object is to provide a fluid pump of simple design and compact arrangement adapted to displace a maximum volume of fluid in a given period of time and so assembled that parts thereof may be readily detached and replaced when and if necessary.

A main object of invention is to provide a simple, effective and durable pump adapted for use in deep wells, for water and oil, and the provision of rotatable means for operating the impeller.

Other objects and advantages of the invention will appear during the progress of this specification. I have shown a preferred form of pump embodying my invention in the accompanying drawings, in which

Fig. 1 is a view of my pump assembled and mounted for use in a deep well, the well casing being shown in section.

Fig. 2 is an enlarged view of the pump partially in section.

Fig. 3 is a sectional plan of the pump on line 3—3 of Fig. 1.

Fig. 4 is a longitudinal section of the pump on line 4—4 of Fig. 3.

Fig. 5 is a transverse section of the pump on line 5—5 of Fig. 4.

Fig. 6 is a bottom end view of the pump on line 6—6 of Fig. 1.

Fig. 7 is a fragmentary section on line 7—7 of Fig. 6.

Fig. 8 is a transverse section on line 8—8 of Fig. 1.

Fig. 9 is an elevation of a well casing with a tandem pump in a deep well casing.

As shown in Fig. 4, the pump proper comprises a composite casing including end members A and A1 and intermediate annular members A2 and A3 which are held together

in operative position by means of a series of bolts A4 extended therethrough. The end members A and A1 have outwardly directed extensions A5 and A6 respectively which support frictionless bearings A7 and A8 in axial alignment for rotatably receiving a shaft B. The ends of the extensions A5 and A6 may be closed by means of caps A9 and A10 respectively, as shown, and the shaft B may be extended through the upper closure A10 as shown for operative connection with a motor M which is mounted in the well casing C, as shown in Fig. 1.

A discharge pipe D is attached to the pump casing A1 by means of the bolts A4 which extend through the flange D1 on said pipe. Internally of the pump casing I provide an impeller E which is operably mounted on a central section B1 of the drive shaft B intermediate the bearing portions B2 and B3 which are rotatably mounted in the bearings A7 and A8 respectively. The pump chamber A11 is annular and is formed intermediate the members A and A1 and internally of the members A2 and A3. The outer periphery A12 of said chamber is spherically formed about the axis of the portion B1 of drive shaft B, while the inner faces A12 and A13 of the members A and A1 respectively are conically formed and provide the sides of the pump chamber.

The central section B1 of the drive shaft which supports the impeller E is inclined at an acute angle to the axis of the bearing portions B2 and B3 so that when the drive shaft B is rotated the impeller E will be oscillated progressively in chamber A11.

The casing members A and A1 have spherically formed annular portions A14 and A15, respectively, which engage the spherically formed periphery E1 of the body E2 of the impeller, and also spherically formed extensions E3 and E4 which are detachably held on the opposite sides of the impeller body. The impeller has an annular vane E5 which engages the wall A12 of the pump chamber at its periphery and is slotted radially at E6 to receive an abutment E7 formed on or attached to the members A2 and A3 of the casing.

The portion B1 of the drive shaft is rotatably supported in the impeller E by means of opposite sets of roller bearings E8, E8 which are held in cones E9, E9 on the portion B1 and engage the beveled faces E10 of the impeller. The cones E9 are held between flanges B4 and B5 which are right angularly disposed relative to the portion B1.

The casing member A is provided with an inlet F at one side of the abutment E7, as shown in Figs. 5 and 6, while the member A1 is provided with an outlet F1 on the opposite side of said abutment. The chamber A11 is in communication with the outlet F1 at opposite sides thereof by means of passages F2 and F3 which are cored in the casing members A, A1, A2 and A3. The outlet F1 is in communication with the chamber D2 of the discharge casing D. Thus, as the impeller vane E5 is rocked or oscillated in the pump chamber A11 a flow of liquid is induced through the inlet F into the pump chamber and is caused to follow a circular path in the chamber and is exhausted through the outlet F1 into the pipe D. The by-passes F2 and F3 which connect the chamber A11 with the outlet F1 serve to relieve and prevent a back pressure when the impeller moves to the left, as seen in Fig. 4, relative to the inlet 30 and outlet.

It will be apparent that the impeller is nonrotatably held by reason of the fact that the abutment E7 in the pump seats in a slot in the impeller vane, as shown in Fig. 5. Therefore, the rotation of the shaft B within the impeller causes the impeller to roll or oscillate progressively at its periphery in a manner similar to the rolling of one cone over another. This action of the impeller varies 40 the area of the pump chamber A11 successively at different points from the inlet to the outlet and effects a continuous flow of fluid through the pump.

My pump is particularly adapted for use 45 in deep wells, as shown in Fig. 1, and may be connected with a motor M which is usually mounted in a casing M1. The motor casing M1 tightly fits the well casing C and is stationarily supported therein by suitable means. The discharge pipe D of the pump telescopes 50 into and is suitably connected with the lower end of the casing M1 so that the fluid discharged from the pump may move upwardly around the periphery of the motor and thence outwardly through a discharge pipe M2. The pump tightly fits the bore of the well casing C so that the oil from the chamber C1 55 below the pump must necessarily be forced through the pump and thence upwardly through the chamber D2 into the chamber M3 of the motor casing and thence outwardly through the pipe M2. The pump shaft B may be connected with the motor shaft M4 by means of a suitable coupling M5.

A pump such as I have described when

employed in a deep well casing is free from valves and other parts which necessarily require attention in order to maintain the pump in operation. Thus my pump may be used in deep wells for sustained periods of 70 time without attention.

In order to provide maximum efficiency in the operation of the pump when used in deep oil or water wells, I may employ two pumps substantially of the character illustrated in Fig. 4 and arranged tandem fashion within the well casing C. In such event the pump would consist of an upper unit U and a lower unit U' connected by a casing U1 having a chamber U2 therein. In this arrangement of pumps the extension A6 on the lower pump unit and the extension A5 on the upper pump unit may be sufficiently elongated and attached together by means of bolts U3 so as to provide the annular chamber U2 between the outlet F1 of the lower pump and the inlet F of the upper pump. The shafts B, B of the tandem arranged pump units are operatively connected by suitable coupling members U5 and U6 connected to said shafts respectively, and the shafts and the coupling devices are housed within the extensions A5 and A6.

The operation of the tandem pump is as follows:

The liquid is drawn from the chamber C' in the well casing C through inlet F into the chamber A11 of the lower pump unit U', and is discharged from the chamber A11 through outlet F1 into the annular chamber U2, from which it is delivered through the inlet F of the pump U to the chamber A11, and from said chamber through outlet F1 to chamber M3 of casing M1, and thence outwardly through discharge pipe M2.

What I claim is:

1. A fluid pump comprising a casing having conical side walls spaced apart and inner and outer spherically formed coaxial walls, extensions formed on opposite sides of said casing having aligned bearings therein, a shaft journaled in said bearing and provided with an intermediate crank portion disposed diagonally relative to the axis of the bearing portions of said shaft, cones mounted on said crank portion, frictionless bearings carried by said cones, an impeller having an enlarged annular inner portion rotatably receiving said bearings, and an annular vane engaging the outer wall of said casing, an abutment held in said casing slidably engaging said vane, inlet and outlet means in the casing on opposite sides of said abutment, and cylindrical members attached to the body of said impeller and engaging the inner wall of the casing, for the purpose described.

2. In a fluid pump, the combination with a shaft having spaced bearing portions and an intermediate crank portion diagonally dis-

posed relative thereto, means for rotatably supporting said shaft, cones detachably mounted on said bearing portion, frictionless bearing members rotatably mounted on said cones, an impeller having an annular body portion with oppositely formed cones engaging said bearing members and an annular vane extending therearound, spherical members detachably held on the body of said impeller and enclosing said bearing members, and a casing having inner and outer spherical walls and conical ends engaging said impeller, as described.

3. A fluid pump as characterized in claim 2, including means formed on said shaft at the extremities of said crank portion for preventing the longitudinal movement of said cones.

4. A fluid pump as characterized in claim 2, including means for preventing the rotation but permitting the oscillation of said impeller when said shaft is rotated.

5. A fluid pump as characterized in claim 2, including a plate stationarily held in said casing, an annular chamber being formed in and between the inner and outer spherical walls of said casing, said plate subdividing said chamber into inlet and outlet portions, and inlet and outlet means connected respectively with said chamber on the opposite sides of said plate.
